RADIO CIRCUIT

Paul Wilson Redcay, Hyde Park, Pa.

Application September 26, 1936, Serial No. 102,757

12 Claims. (Cl. 250—20)

My invention relates to an improved radio receiving circuit and more particularly to a receiver of the type in which two different frequencies are employed during transfer of the signal energy in 5 the circuit.

Heretofore it has been customary to provide ten kilocycle separation selectivity in the average radio receiver since broadcast stations merely modulated with an audible signal up to 5000 10 cycles. More recently, however, an increasing number of radio transmitters have been designed to transmit high fidelity programs which necessitates modulation frequencies as high or higher than 15,000 cycles. While it is desirable to provide a radio receiver capable of receiving such high fidelity broadcasts, it is often necessary to provide in the same receiver a provision for a 15 selectivity capable of differentiating between signal energies separated by ten kilocycles. It also 20 has been found in providing sufficient amplification for the reception of high fidelity programs, that the background noise of the usual type of radio receiver is relatively high and undesirable.

It is therefore an object of my invention to provide 25 an improved radio receiving system which will overcome certain limitations of the arrangements of the prior art.

Another object of my invention is to provide 30 an improved radio receiver capable of amplifying signal energies of at least 30 kilocycles in width, without impairing the side-bands thereof, and also obtaining at least ten kilocycles selectively between signal energy received from other stations.

Still another object of my invention is to provide 35 an improved radio receiving system wherein signal energy at a certain frequency is rectified and transmitted to an amplifier at a harmonic of said certain frequency.

A still further object of my invention is to increase 40 the gain and sensitivity of the usual type of superheterodyne receiver while maintaining a relatively low background noise.

A still further object of my invention is to provide 45 a superheterodyne receiver using two intermediate frequencies, one of which is a harmonic of the other, and in which the signal transfer means between the two intermediate frequency amplifiers is of the diode detector and electron capacitance coupled type.

The novel features which are believed to be 50 characteristic of my invention are set forth with particularity in the appended claims. My invention itself, however, both as to its organization 55 and method of operation, together with further objects and advantages thereof, will be better understood by reference to the following description taken in connection with the accompanying drawings in which Fig. 1 represents the preferred embodiment of my invention, and Fig.

2 is a modification thereof. Fig. 3 represents an embodiment of my invention employing a simplified arrangement of the coupling device in which the grids have been eliminated. Figs. 4, 5 and 6 are illustrative of different types of 5 receiving circuits in which the coupling device of my invention may be employed.

Referring to Fig. 1 of the drawings, modulated radio frequency signal energy picked up by an antenna 1 may be impressed upon the grid circuit 2 of a radio frequency amplifier device or tube 3, this circuit 2 being tunable to the signal energy by means of a variable capacitor 4. The output circuit of the amplifier 3 is coupled to the grid circuit 5 of a first frequency converter 10 or detector device or tube 6, the grid circuit being tunable to the signal energy by a variable capacitor 7. While the first frequency converter or detector 6 is shown as being a discharge device of the multiple purpose type provided with 15 an oscillator circuit 8 tunable to the proper frequency by a variable capacitor 9, any of the types of frequency converters or detectors known in the art may be employed. As is common practice in the art, the variable capacitors 4, 7 and 20 25 9 are of the unit control or gang capacitor type, and while the oscillator circuit 8 is shown as being tunable by a single capacitor, it may employ auxiliary or padding capacitors.

The output circuit of the first detector 6 and 30 the input circuit 10 of an intermediate frequency amplifier device 11 are coupled together by means of the windings of a tuned intermediate frequency transformer. The output circuit of the intermediate frequency amplifier device 11 and the input circuit 12 of a diode rectifier and electron capacitance coupling device 13 are coupled together by means of a similar intermediate frequency transformer. Both these intermediate 35 transformers are preferably tuned so as to have 40 relatively flat topped resonance characteristics. The output or anode circuit of the diode rectifier and electron capacitance coupling device 13 includes the primary winding of an intermediate frequency transformer, the secondary windings 45 of which are included in the grid circuit 14 of the electron discharge device 15 which comprises the first stage of amplification in the second intermediate frequency amplifier. The second stage of amplification in this amplifier is connected to the output circuit of the intermediate frequency amplifier device 15 through a second intermediate frequency transformer, the secondary 50 windings of which comprise the input circuit 16 of an intermediate frequency amplifier device 55 17. The two intermediate frequency transformers included in the grid circuits 14 and 16 are preferably of the adjustable coupling type which are so tuned that when in the position of maximum selectivity the resonance characteristics of 60

each is considerably sharper than the resonance characteristics of the intermediate frequency transformers used in the first intermediate frequency amplifier. The second intermediate frequency amplifier operates at a higher frequency than the first intermediate frequency amplifier, and this frequency is preferably a harmonic of the frequency at which the first intermediate frequency amplifier operates.

10 The output circuit of the amplifier device 17 is coupled to the input circuit 18 of a diode second detector and amplifier device 19, by means of an intermediate frequency transformer which has a relatively sharp resonance characteristic. The anode or output circuit of the triode amplifier portion of the device 19 operates as an audio-frequency amplifier which is coupled through a resistance capacitance coupling arrangement 20 to the power amplifier device 21. The amplified audible frequency signal energy of the output circuit of the power amplifier device 21 is transmitted by means of a suitable transformer 22 to a translating device such as a dynamic speaker 23. The magnetic field 25 for the dynamic speaker 23 is provided by a field winding which is included as a reactor in a filter circuit 24 of a power supply apparatus which comprises a transformer 25 and a rectifier device 26. The transformer 25 which is energized 30 from a suitable source of alternating current is provided with additional secondary windings 27 and 28 which supply energy for the cathodes of the various electric discharge devices. The device 13 which I have called a linear or diode 35 rectifier and electron-capacitance coupling device comprises an electron discharge device having a cathode, an anode and a diode plate. This device operates in a manner which will become apparent in subsequent description of the operation 40 thereof, due to the fact that the cathode is a common source of electrons for the anode and the diode plate, and that there are certain inter-electrode capacitances present between these three elements. While I do not wish to 45 be limited thereto, I believe that the explanation of the operation of the linear rectifier and electron-capacitance coupled device 13 presents with present knowledge the most likely theory of operation of the device and circuit arrangement shown herein.

50 The input circuit 12 of the diode rectifier and electron capacitance coupling device 13 includes a resistor 29 suitably bypassed by a capacitor 30 to provide a suitable gain control bias for the 55 radio frequency amplifier device 3 and the first intermediate frequency amplifier device 11. By rectifying the signal energy impressed upon the input circuit 12, an automatic gain control bias is developed across the resistor 29 which is impressed upon the grid circuit of the radio frequency amplifier device 3 through a conductive connection including a resistor 31, and this potential is also impressed upon the grid circuit 60 of the first intermediate frequency amplifier device 11 through a conductive connection including the resistor 32. The electric discharge device 13 in addition to the diode rectifier portion includes the electrodes normally providing a pentode amplifier. In the arrangement shown, 65 however, all of the grids of the pentode portion of the discharge device 13 are connected together with the cathode. The anode circuit of the pentode portion of the discharge device 13 includes the primary winding of an intermediate frequency transformer, the secondary winding of which

is connected in the grid circuit 14 of the second intermediate frequency amplifier device 15.

The input circuit 18 of the second detector device 19 is arranged so as to comprise a half wave diode rectifier circuit which includes the series connected resistors 33 and 34. The rectification of the signal energy by the input circuit 18 causes a variable voltage to be developed across the resistors 33 and 34, which voltage is utilized as an automatic gain control voltage 10 for the second intermediate frequency amplifier devices 15 and 17. The conductive connection from the resistor 34 including the resistor 35 and the resistor 36 permits this control bias to be impressed upon the grid circuit 14 of the intermediate frequency amplifier 15. Likewise a conductive connection from the resistor 34 including the resistor 35 and the resistor 36 permits this bias to be impressed upon the grid circuit 16 of the intermediate frequency amplifier device 17.

It will, of course, be obvious that where a device of the diode-triode type of suitable characteristics is available, such device may be substituted for the device 13 shown, and the grid 25 of the triode portion of the device would be connected to the cathode. It is furthermore within the scope of my invention to utilize other forms of diode-electron capacitance coupling devices one type of which is shown in Fig. 3 having suitable characteristics and which do not permit undesired coupling or feed back between the two intermediate frequency amplifiers.

Since the remaining circuit elements are arranged in accordance with the usual engineering 35 practice, it is believed that no further description thereof is necessary since the operation of the receiver will be apparent to those skilled in the art, and the receiver shown is merely illustrative of one type of receiver to which my invention may be applied. In general the operation of the receiver is as follows: The radio frequency amplifier input circuit and the first detector input circuit are tuned to receive high frequency signal energy picked up by the antenna 1. The oscillator circuit 9 is simultaneously tuned so as to provide in the output circuit of the detector device 6 signal energy of an intermediate frequency, for example, of 150 kilocycles. The intermediate frequency transformers connected between the electron discharge devices or tubes 6, 11 and 13 are tuned so as to be resonant to this frequency. The signal energy which is at 150 kilocycles is rectified by the diode circuit including the resistor 29. As is well understood by those skilled in the art, the voltage developed across the resistor 29 when applied to the grid circuits of the tubes 3 and 11 through the resistors 31 and 32, respectively, will operate to maintain the 60 energy level at tube 13 at a substantially constant value. As is well known, the rectification of the signal energy received by the input circuit 12 of the tube 13 produces not only the audio-frequency signal but also fundamental and 65 harmonic components of the carrier frequency. Certain of the fundamental and harmonic components of the carrier frequency together with a modulation of the components may be obtained in the output circuit of the tube 13. The electrodes of the pentode portion of the tube 13 are so arranged as to provide an electron capacitance coupling device to facilitate the transfer of the signal energy. The primary winding of the intermediate frequency transformer which is con- 75

nected in the anode-cathode circuit of the tube 13 is tuned to a harmonic of the intermediate frequency of the first intermediate frequency amplifier. While any harmonics of the operating frequency of the first intermediate frequency amplifier may be utilized, I prefer to employ the third harmonic frequency and thus the signal energy impressed upon the intermediate frequency amplifier tubes 15 and 17 is a third harmonic of the first intermediate frequency or, as has been assumed, it is at a frequency of 450 kilocycles. The amplification of the second intermediate frequency amplifier tubes 15 and 17 is controlled by an automatic gain control circuit which derives its gain control bias from the diode rectifier circuit of the second detector and audio amplifier tube 19. Since this automatic gain control feature operates in the conventional manner, no detailed explanation thereof will be made. The audio-frequency component resulting from the rectification of the signal energy in the circuit 18 is impressed upon the grid of the triode section of the tube 19 by means of an adjustable contact on resistor 33. The triode portion of the tube 19 therefore operates as the first audio-frequency amplifier which is resistance capacitance coupled to the second audio-frequency amplifier.

While I have used for illustration 150 and 450 kilocycles as the first and second intermediate frequency amplifier frequencies, it will be understood that my invention is not limited to the use of these particular frequencies but other frequencies having a harmonic relation to each other may be used instead. It will also be apparent that by having the coupling between the primary and secondary windings of the intermediate frequency transformers 14 and 16 adjustable the selectivity of the receiver may be readily controlled.

In the modification of my invention shown in Fig. 2, a diode-triode tube is utilized in place of the diode-pentode tube. In this case the intermediate frequency transformer comprising the input circuit 12 and the bias resistor 29 together with the bypass capacitor 30 operates in the same manner as the arrangement disclosed in Fig. 1. The various signal components appearing in the diode circuit, however, are coupled through the capacitor 41 to the grid of the diode-triode tube 40. A suitable grid resistor 42 is connected between this grid and the cathode. In the modification of my invention shown in Fig. 3, a tube 43 is employed in which the grids have been eliminated and a suitable resistor 44 and capacitor 45 inserted in the cathode circuit. In each of these modifications the anode circuit includes the primary winding of the higher frequency intermediate frequency transformer, the secondary winding of which is included in the grid circuit 14.

I have found that by using two intermediate frequency amplifiers, the second one operating at a harmonic of the frequency of the first amplifier, a very high degree of gain is secured with a minimum of background noise and an entire absence of oscillation in the receiver. This arrangement also provides an apparent selectivity of at least ten kilocycle separation between stations while transmitting modulation components considerably in excess of the 5000 cycle limit.

It will be apparent to those skilled in the art that any number of intermediate frequency amplifiers may be utilized, each coupled to the suc-

ceeding one by a coupling circuit utilizing the linear detector and electron capacitance coupling device of my invention to rectify the received signal energy and to transmit signal energy at a harmonic of the frequency of the received signal energy as indicated in Fig. 4. Furthermore, if desired, the first intermediate frequency amplifier may be omitted and signal energy may be transmitted directly from the first detector or frequency convertor to the linear rectifier and electron capacitance coupling device as indicated in Fig. 5. It has also been found that the coupling circuit of my invention may be employed between radio frequency amplifiers in a receiver of the tuned radio frequency type which has been indicated in Fig. 6.

While this invention has been shown and described in connection with certain specific embodiments it will, of course, be understood that it is not to be limited thereto, since it is apparent that the principles herein disclosed are susceptible of numerous other applications, and modifications may be made in the circuit arrangement and in the instrumentalities employed without departing from the spirit and scope of my invention as set forth in the appended claims.

Having thus described certain embodiments of my invention what I claim as new and desire to secure by Letters Patent is:

1. In a radio receiver, the combination of a source of signal energy, an amplifier operating at a harmonic of the frequency of said signal energy, and a diode rectifier and electron capacitance coupling device arranged to rectify signal energy received from said source and to transmit signal energy to said amplifier at said harmonic frequency.

2. In a radio receiver, the combination of a source of signal energy, an amplifier operating at a harmonic of the frequency of said signal energy, a coupling circuit including input and output circuits, said input circuit being resonant to the frequency of said source of signal energy and being coupled thereto, said output circuit being coupled to said amplifier, and a linear detector and electron capacitance coupling means comprising an electron discharge device interconnecting said input and output circuit, said device operating to rectify signal energy received from said source and to supply signal energy to said amplifier.

3. A radio receiver including a source of signal energy at a certain frequency, an amplifier operating at a harmonic of said certain frequency, means interconnecting said source and said amplifier comprising a linear rectifier and electron capacitance coupling device for rectifying signal energy received from said source, for supplying to said source an automatic gain control bias and for supplying signal energy at said harmonic frequency to said amplifier, and means arranged to rectify signal energy received from said amplifier and to provide an automatic gain control bias for said amplifier.

4. A superheterodyne radio receiver including a source of signal energy, an intermediate frequency amplifier operating at a harmonic of the frequency of said source, a coupling circuit interconnecting said source and said amplifier, said circuit including an input circuit resonant to the frequency of said source, an output circuit coupled to said amplifier and resonant to the operating frequency thereof, and a linear detector and electron capacitance coupling means interconnecting said input and output circuits, said

- means operating to rectify signal energy received from said source and to transmit at said harmonic frequency signal energy to said amplifier by electron capacitance coupling action.
5. A radio receiver including a source of signal energy at an intermediate frequency, an intermediate frequency amplifier operating at an odd harmonic of the frequency of said source, a coupling circuit connected between said source and 10 said amplifier, said circuit including an input circuit resonant to the frequency of said source, an output circuit coupled to said amplifier and resonant to the operating frequency of said amplifier, and a linear detector and electron capacitance coupling means interconnecting said input and output circuits, said means operating to rectify signal energy received from said source and to transmit at said harmonic frequency signal energy to said amplifier by electron capacitance 20 coupling action.
6. In a radio receiver including an intermediate frequency amplifier, a second intermediate frequency amplifier operating at a frequency three times the frequency of said first amplifier, a coupling circuit including an input circuit coupled to 25 said first amplifier and resonant to the frequency thereof, an output circuit coupled to said second amplifier and resonant to the frequency thereof, a linear rectifier and electron capacitance coupling means comprising an electron discharge device interconnecting said input and output circuits, said device operating to rectify signal energy received from said first amplifier and to couple said rectifier input circuit to said output circuit by electron capacitance coupling.
7. In the superheterodyne receiver, the combination of a first intermediate frequency amplifier, a second intermediate frequency amplifier operating at a third harmonic frequency of the operating frequency of said first amplifier, means 40 for transferring signal energy from said first amplifier to said second amplifier comprising a multi-electrode discharge device arranged to operate as a diode detector and an electron capacitance coupling means, said diode detector operating to rectify said signal energy and to supply an automatic gain control bias for said first amplifier, and said electron capacitance coupling means operating to supply signal energy to said 45 second amplifier.
8. In a superheterodyne receiver, the combination of a first intermediate frequency amplifier, a second intermediate frequency amplifier operating at a higher frequency than said first amplifier, means for transferring signal energy from 50 said first amplifier to said second amplifier including a diode detector and an electron capacitance coupling means, said detector operating to provide an automatic gain control bias for said first amplifier, and means comprising a second detector for translating said signal energy into audio frequency energy and for providing an automatic gain control bias for said second amplifier.
9. A radio receiver of the superheterodyne type comprising an oscillator, a first detector, a low frequency intermediate frequency amplifier, a higher frequency intermediate frequency amplifier, means coupling said intermediate frequency amplifiers together comprising a diode rectifier connected to receive signal energy from said first 55 amplifier, to supply thereto an automatic gain control bias, and to supply signal energy to said second amplifier, and a second detector including means for deriving an automatic gain control bias for said second amplifier.
10. In a receiver of the superheterodyne type, means for converting an incoming modulated signal to an intermediate frequency, an intermediate frequency amplifier for amplifying said converted signal, means for rectifying said converted signal including means for supplying an automatic gain control bias to said amplifier, a second intermediate frequency amplifier operating at a frequency which is a harmonic of the first intermediate frequency, means for transmitting from 15 said rectifying means a signal to said second amplifier for amplification thereby, means for detecting and translating the signal received from said second amplifier, and means for obtaining an automatic gain control bias from said latter 20 means to control the amplification of said second amplifier.
11. In a radio receiver of the superheterodyne type, the combination of an intermediate frequency amplifier including transformers having 25 a flat top resonance characteristic, a rectifier circuit for receiving signal energy from said amplifier, means included in said circuit for generating an automatic gain control bias, means for applying said bias to said amplifier to maintain at 30 a substantially constant level the energy supplied to said rectifier circuit, a second intermediate frequency amplifier including transformers sharply resonant to the third harmonic of the frequency of said first amplifier, electron capacitance coupling means for transferring signal energy from said rectifier circuit to said second amplifier, a detector circuit for translating energy received from said second amplifier into audio frequency energy, said detector circuit including 40 means for generating an automatic gain control bias, and means for applying said bias to said second amplifier to control the amplification thereof.
12. In combination, a radio frequency amplifier, means for converting signal energy received therefrom to an intermediate frequency, an intermediate frequency amplifier including transformers having a flat top resonance characteristic, a rectifier circuit for rectifying signal energy received from said amplifier, means included in 45 said circuit for generating an automatic gain control bias, means for applying said bias to said radio frequency amplifier and said intermediate frequency amplifier whereby the signal energy 50 level at said rectifier circuit is maintained relatively constant, a multi-stage second intermediate frequency amplifier including transformers sharply resonant to the third harmonic of said first intermediate frequency, the electron capacitance coupling means for transferring signal energy from said rectifier circuit to said second intermediate frequency amplifier, a detector circuit for translating into audio frequency energy signal energy received from said second intermediate 55 frequency amplifier, means including in said detector circuit for generating a second automatic gain control bias, and means for applying said bias to each stage of said second intermediate frequency amplifier.

PAUL WILSON REDCAY.
